UNITED STATES PATENT OFFICE.

FREDERICK J. MANSFIELD, OF PASADENA, CALIFORNIA.

FULLING-MACHINE.

1,158,257.

Specification of Letters Patent. Patented Oct. 26, 1915.

Application filed May 31, 1913. Serial No. 771,070.

To all whom it may concern:

Be it known that I, FREDERICK J. MANSFIELD, a citizen of the United States, residing at Pasadena, in the county of Los Angeles and State of California, have invented a new and useful Fulling-Machine, of which the following is a specification.

This invention relates to fulling machines and the main object of the invention is to provide a machine which will have a much greater capacity for a given size than other machines, of which I am aware. In such machines the usual custom is to secure the ends of the cloth together in such a manner as to form a continuous belt and to propel the belt through the machine. This manner of propelling the cloth belt took up considerable room on account of the drawing action of the cloth which rendered a considerable length of it taut, hence no convolutions with a resultant loss of capacity. In my invention I move the cloth through the machine in an entirely different manner. Instead of fastening its ends together to form a belt I leave the ends unfastened and place the cloth in the machine in a promiscuous way and provide the machine with internal, moving, corrugated surfaces, which act upon the cloth and carry it around inside of the machine giving it the necessary movement, these corrugated surfaces being effected to move the cloth upon contact with it while it is in a crumpled condition. By placing the cloth in the machine in this manner I am enabled to get a much greater amount of cloth inside a machine of a given size.

Another object of the invention is to provide for expanding certain of the corrugated rolls thus reducing the internal volume of the machine when a smaller amount of cloth is inserted in order to maintain the proper contact of the corrugated portions with the cloth and give the cloth the necessary propulsion.

Referring to the drawings: Figure 1 is a side elevation of the machine. Fig. 2 is a front elevation with part of the machine broken away to show the interior. Fig. 3 is an end elevation of a portion of the machine with the gearing removed. Fig. 4 is a perspective of one of the expanding rolls. Fig.

5 is an enlarged section through one of the internal gear retaining rolls. Fig. 6 is a side elevation on an enlarged scale, of part 55 of the expanding mechanism. Fig. 7 is a longitudinal section on line 7—7, Fig. 4. Fig. 8 is a section on line 8—8, Fig. 7. Fig. 9 is an end view of one of the end plates of an expanded roller. Fig. 10 is a section 60 on line 10—10, Fig. 2.

The machine comprises a cylindrical drum 1 having a sliding door 2. The wall of the cylinder 1 is provided with openings into which project corrugated rollers 3, 3^a, 3^b and 65 3^c which are of varying sizes, as shown in Fig. 10. The drum is also provided with offset housings 4 in which are corrugated rollers 5 and 5^a. These rollers are expandable circumferentially, as will be described. 70 In the center is a corrugated roller 6. The diameters of the rollers 3 and 6 and their relative positions in the drum are such as to provide a passage between said rollers, through which passage the cloth is carried 75 in the manner hereinafter fully described. The drum 1 is stationary and the rollers are caused to rotate by suitable gearing, as will be described. 7 is a sliding abutment, which is adjustable radially in the drum 1 80 to cause its inner portion to project a greater or less distance from the wall of the drum and thereby act to partially turn the cloth as it falls, as will be explained. The abutment 7 is provided with a series of holes 85 7^a which are engaged by a spring latch 7^b to lock the abutment when adjusted to various positions.

The cloth is placed through the door 2 into the machine and is not arranged in any 90 definite way except that it is irregularly crumpled or folded and laid in such a way that the general longitudinal dimension of the cloth lies circumferentially of the drum. As the corrugated rollers revolve the corrugations which project against the cloth move the cloth along around the drum in the direction of the arrow, Fig. 10, and carry it up around to the top of the drum, and from the top the cloth falls down upon the abutment 7 and commences another circuit. The movement of the cloth around the drum produces the bending and pressing required for fulling it, and the abutment 7 acts to insure 95 100

that the cloth will be turned each time that it rotates so that there is no possibility of the cloth being subjected a second time to exactly the same contact with the rollers. 5 If a less amount of cloth is used, the abutment 7 is moved farther in to bring the falling cloth closer to the roller 6, and I also provide for expanding the rollers 5 and 6 to give the necessary grip upon the cloth 10 when there is a less amount in the machine. The roller 6 is mounted upon a shaft 8 which is driven by a pulley 9, as shown in Fig. 1, and a gear 10 is mounted on shaft 8 and meshes with gears 11, which are respectively mounted on shafts 12, which carry 15 the respective expandable rollers 5 and 5^a. A pinion 13 is mounted on a shaft 14 which carries one of the rollers 3, the other roller 3 being mounted on a similar shaft 14 and 20 equipped with a sprocket 15. The roller 3^a is carried on a shaft 16 with sprocket 17. The next roller 3^a is carried on a shaft 18 with sprocket 19 and the second roller 3^b is carried on shaft 20 with a similar sprocket 25 20^a, and the roller 3^c is carried on a shaft 21 with sprocket 22. All these mentioned sprockets are operated by a chain 23 which is held in proper relation by idle sprockets 24, so that as the pulley 9 revolves, the center shaft 8 operates through a pulley 9^a, belt 9^b, pulley 9^c and the aforementioned sprocket gearing drives all of the elevating rollers. 30 The rollers 6 and 5 act together to impart the necessary annular movement to the cloth so as to force the cloth through the passage 35 between the roller 6 and the rollers 3. The corrugations of the roller 6 are relatively coarse for the purpose of feeding the cloth between the rollers and for agitating and 40 bending the cloth upon itself, as it is so fed, while the corrugations of the rollers 3 are relatively fine. The action of the rollers 3 in conjunction with the roller 6 is such as to compress the cloth so as to draw the meshes 45 of the fabric closer together.

Practice has shown me that to obtain the best results when fulling cloth, various pressures and bendings must be produced so as to properly affect the different lengths of 50 fibers. The fibers usually found in a piece of cloth generally fall into four classes, that is, long fibers, medium length fibers, short fibers, and very short fibers. It is best to start the long fibers fulling first, and hence 55 I provide the large roller 5 near the entrance to the casing. This roller coacting with the roller 6, produces a pressing and binding action best adapted to the long fibers. The cloth next passes between the 60 roller 6 and the very small rollers 3, and the intensity of the pressing and bending action is greatly diminished, so that the very short fibers will begin to full. The intensity of the bending and pressing action required 65 is inversely proportional to the length of

the fibers, and I have taken this fact into consideration and provided rollers of different diameters. As the cloth moves between the roller 3^a and the central roller, the next to the shortest fibers full and the roller 3^b cause the medium length fibers to full. It is 70 essential that the pressure be increased as the cloth passage more nearly approaches the vertical, for otherwise the cloth would not feed properly since the force required to 75 raise the same increases in direct proportion to the incline increase. I have also found that the more sudden the changes in the pressing and bending action the better the fulling operation will be performed, and 80 therefore I provide the small roller 3^c, which causes the pressure to be suddenly reduced, and then I provide the large expansive roller 5^a which again increases the bending and 85 pressing action on the cloth.

The intensity of the bending action is dependent upon the diameter of the coacting rollers to a great extent, and also upon the size of the corrugations. For instance, the large rollers 5, 5^a coact with the large roller 90 6 and produce an intense bending action upon the cloth since the latter is forced into the channels formed by the corrugations. The small rollers 3, 3 have smaller corrugations than the rollers 5, 5^a, and do not cause 95 the cloth to be bent so severely. They also reduce the pressure on the cloth.

The side of the drum has removable sections 25 with handles 26 and bolts 27 employed for locking the section 25 in place. 100 These bolts may be of any desired construction and form no essential part of the invention.

The expanding rollers 5 which are preferably, though not necessarily of wood, are 105 constructed as shown in Figs. 4 to 9 inclusive, each consisting of a plurality of segmental leaves 28 with intermediate small leaves 29 arranged to fit concave surfaces 30 on leaves 28. The small intermediate leaves 110 29 have sockets 31 at each end, each socket 31 loosely receiving the end of an arm 32, each arm 32 being hinged to a hub 33 which hubs are mounted on a threaded shaft 34, carrying pinions 35 at each end. The threads at 115 the respective ends of the shafts 34 are in a reverse direction to each other. By revolving shaft 34 the hubs 33 may be moved toward or from each other, and as the hubs are moved away from each other they act to 120 swing the arms 32 into a position more nearly at right angles to shaft 34 and thereby move the leaves 29 outwardly while by moving the hubs 33 toward each other the leaves 29 are brought inward. The large 125 outer leaves 28 are supported by a similar structure except that the arms 32' thereof are shorter as shown in Fig. 8. Thus when the outer leaves 28 are moved outwardly to expand the roller the inner leaves 29 are 130

moved correspondingly outward to fill the gaps which necessarily are formed between the radially moving leaves 28.

The shafts 34 are rotatably mounted in plates 36 in the ends of the roller as shown in Fig. 7, and outer plates 37 are arranged outside the plates 36 as shown in detail in Fig. 9, the outer plates 37 having enlarged openings 38 which give access to the ends of shafts 34, the latter being provided with square ends 39 for enabling a wrench to be applied for turning them.

The pinions 35 mesh with an annular gear 49 which, as shown in detail in Fig. 5, is revolvably supported on bushings 41, which are retained by bolts 42 screwed into the end plates 37, so that when any one of the pinions 35 is rotated all of the others are correspondingly actuated. An annular internal gear 44 is revolvably mounted on retaining bushings 45 which are similarly mounted to bushings 41, having bolts 46 which are screwed into the intermediate leaves 29, and pinions 47 mesh with the gear 44 with two intermediate pinions 48 between the pinions 35 and 47 acting to transmit the power, so that simultaneous rotation of threaded shafts 34 is secured. Thus when it is desired to enlarge or reduce the area of a roller a wrench is applied to the square head 39 of one of the threaded shafts and rotated whereupon the aforescribed gearing causes the leaves 28 and 29 to be moved in or out according to the direction in which the threaded shafts 34 are turned.

What I claim is:

1. In a fulling machine, a stationary drum, a corrugated roller extending centrally through the drum, a plurality of corrugated rollers spaced from said first mentioned roller and having their axes parallel thereto, and in an arc concentric with the drum, said rollers projecting into the drum through openings formed in the wall thereof.
2. In a fulling machine, a stationary drum, a corrugated roller extending longitudinally through the center of said drum, the wall of the drum being formed with a plurality of openings, and a plurality of corrugated rollers of different diameters revolvble in said openings and projecting into the drum, the axes of said second mentioned rollers being parallel to the axis of the first mentioned roller.
3. In a fulling machine, a stationary drum provided with a plurality of offset housings communicating with the interior thereof, a corrugated roller extending longitudinally through the center of the drum, a corrugated roller revolvble within each of said housings and projecting into the drum, the wall of the casing being formed with a plurality of openings, and a plurality of corrugated rollers arranged to revolve within said openings and to project into the drum,

all of said rollers having their axes parallel to each other.

4. In a fulling machine, a stationary drum provided with a plurality of offset housings communicating with the interior thereof, a corrugated roller extending longitudinally through the drum at the center thereof, and an expansive corrugated roller arranged to revolve within each of said housings and to project into the drum to coact with said first mentioned roller.

5. In a fulling machine of the character described, a stationary drum formed with an offset housing communicating with the interior thereof, a corrugated roller extending centrally through said drum, an expansive corrugated roller revolvble within said housing and projecting into said drum to coact with said first mentioned roller, and a plurality of smaller corrugated rollers arranged in an arc concentric with said first mentioned roller and projecting into the drum to coact with the latter.

6. In a fulling machine, a stationary drum, an expansive corrugated roller extending centrally through said drum, a plurality of non-expansive corrugated rollers, and a plurality of expansive corrugated rollers, the second and third mentioned rollers being arranged around the first mentioned roller in spaced parallel relation thereto and projecting into the drum.

7. A fulling machine comprising a drum, a plurality of corrugated rollers with their corrugated leaves extending into the drum, certain of said rollers being expandible, each expandible roller comprising segmental outer leaves, segmental intermediate leaves between the outer leaves, threaded shafts inside the expandible roller, hubs on the threaded shafts, arms pivoted to the hubs, said arms connected to the outer leaves and to the intermediate leaves, and gearing for simultaneously rotating said threaded shafts.

8. In a fulling machine, a stationary drum formed with a pair of offset housings communicating with the interior thereof, an expansive roller extending centrally through the drum, an expansive corrugated roller housed within each of said housings, and a plurality of non-expansive corrugated rollers, the second and third mentioned rollers being arranged in spaced parallel relation to the first mentioned roller and projecting into the drum to coact with the latter.

9. In a fulling machine, a drum, a roller within said drum, a series of rollers coacting with said first roller for fulling the cloth, an abutment extending into said drum, and means for adjusting said abutment toward or away from said first roller.

10. In a fulling machine, a drum, a plurality of leaf rollers with their leaves extending into the drum, certain of said rollers being expandible, each expandible roller com-

prising segmental outer leaves, segmental intermediate leaves between the outer leaves, threaded shafts inside the expansible roller, hubs on the threaded shafts, arms pivoted 5 to the hubs, said arms connected to the outer leaves and to the intermediate leaves, and gearing for simultaneously rotating said threaded shafts.

In testimony whereof, I have hereunto set my hand at Los Angeles, California, this 10 23d day of May, 1913.

FREDERICK. J. MANSFIELD.

In presence of—

GEO. T. HACKLEY,
MARTHA M. LANGE.

Copies of this patent may be obtained for five cents each, by addressing the "Commissioner of Patents. Washington, D. C."

Correction in Letters Patent No. 1,158,257.

It is hereby certified that in Letters Patent No. 1,158,257, granted October 26, 1915, upon the application of Frederick J. Mansfield, of Pasadena, California, for an improvement in "Fulling-Machines," an error appears requiring correction as follows: In the drawings, Sheet 1, for Figure 1 as shown in the patent read Figure 1, as here shown;

and that the said Letters Patent should be read with this correction therein that the same may conform to the record of the case in the Patent Office.'

Signed and sealed this 22d day of August, A. D., 1916.

[SEAL.]

F. W. H. CLAY,

Acting Commissioner of Patents.
